UNITED STATES PATENT OFFICE

DENNIS C. O'SHEA, OF CHICAGO, ILLINOIS

HIP PAD

Application filed May 26, 1932. Serial No. 613,721.

This invention relates to improvements in hip pads and, more especially, such devices adapted for athletes engaging in sports, such as football, basketball, or the like, in which they are exposed to injury.

The device is so constructed as to afford protection to the hips and base of the spine, at the same time affording freedom of motion and action.

10 Among the features of the invention is the provision of means adapted to hook under the belt of the wearer to assist in holding the trousers up and the pad down.

15 Other features and advantages of my invention will appear more fully as I proceed with my specification.

In that form of device embodying the features of my invention shown in the accompanying drawings—

20 Figure 1 is a view in perspective looking from the front slightly to one side; Fig. 2 is a view taken as indicated by the line 2 of Fig. 1; Fig. 3 is an enlarged fragmentary view similar to Fig. 2, showing one of the projecting members adapted to hook under the belt; Fig. 4 is a view in perspective from the rear slightly to one side; and Fig. 5 is a view taken as indicated by the line 5 of Fig. 4.

25 As shown in the drawings, the device includes a padded waist band 10 open in front and adapted to be held together by the strap 11 and buckle 12. This band is preferably made of suitable padded or quilted material. For example, the band may have double walls 10^a and 10^b with padding 10^c between. 10^d may indicate quilting stitches to hold the padding 10^c in place. The upper edge of the waist band 10 is designed to encircle the body of the wearer slightly above the hips. Said waist band is widened at the sides and rear to form projections extending substantially below the waist. Said projections at the sides are indicated by 13 and 14 and the projection in the rear is indicated by 15.

30 The side projections carry lower hip protecting plate members 16 and 17 made out of any suitable material, for example, leather, fibre, or the like. The rear projection 15 carries a pair of spine-protecting plate mem-

bers 18, 18, the lower ends of said members being designed especially to bend somewhat under the body of the wearer and protect the base of the spine.

35 The waist band 10 also carries on each side above the plate members 16 and 17, upper hip-protecting plate members 16^a and 17^a, respectively, made of leather, fibre, or similar material. 16^b and 17^b indicate hip-protecting bridging members to bridge the spaces between the upper and lower plates. These members are preferably attached to the upper plates by lacing 19, said lacing permitting relative movement between the upper plates and bridging plates and sliding movement between the bridging plates and lower plates. This construction affords the wearer considerable freedom of movement.

40 Under the spine-protecting plates 18, 18, the padding 10^c in the waist band is preferably thickened or bulged inwardly, as indicated by 10^e, 10^d. Likewise, said padding is thickened under the lower hip plates 16 and 17, as indicated by 10^c, and under the upper hip plates 16^a and 17^a, as indicated by 10^f.

45 Mounted on each of the upper hip plates 16^a and 17^a is a horizontally arranged elongated tubular projecting member 20 made of leather or similar material. These members are adapted to hook under the belt of the wearer and serve to hold the pad device down and the trousers up. As here shown, the tubular members 20 are provided with rubber tubes 21 inside and thus said members 20, in addition to performing the function just stated, act as cushions or pads, thus affording additional protection to the wearer against injury. As here shown, the members 20 are sewn to the plates 17 by the stitching 22 and 23. The lower edge of each member 20, as indicated by 20^a, is provided with holes 20^b which accommodate the lacing 19 serving to attach the plates 16^b and 17^b.

50 While I have shown and described certain embodiments of my invention, it is to be understood that it is capable of many modifications. Changes, therefore, in the construction and arrangement may be made without departing from the spirit and scope 55 of the invention as disclosed in the appended

claim, in which it is my intention to claim all novelty inherent in my invention as broadly as permissible, in view of the prior art.

What I regard as new, and desire to secure by Letters Patent, is:

A device of the character described, including; a waist band widened at the sides and rear to form projections extending substantially below the waist; hip-protecting

10

plate members on the side projections; a spine-protecting plate member on the rear projection; and horizontally arranged elongated resilient tubular projecting members at the sides, said members adapted to hook under the belt of a wearer.

In witness whereof, I have hereunto set my hand, this 15th day of February, 1932.

DENNIS C. O'SHEA.
